UNITED STATES PATENT OFFICE.

FREDERICK C. HOWARD, OF SPOKANE, WASHINGTON, ASSIGNOR OF ONE-HALF TO
FREDERICK C. DAHLIN, OF SPOKANE, WASHINGTON.

CHRONOMETRIC-SPRING INDICATOR.

1,101,443.

Specification of Letters Patent. Patented June 23, 1914.

Application filed March 28, 1913. Serial No. 757,461.

To all whom it may concern:

Be it known that I, FREDERICK C. HOWARD, a citizen of the United States, residing at Spokane, in the county of Spokane and State of Washington, have invented certain new and useful Improvements in Chronometric-Spring Indicators; and I do hereby declare the following to be a full, clear, and exact description of the invention, such as will enable others skilled in the art to which it appertains to make and use the same.

This invention relates to improvements in winding indicators for watches and the like, and has particular reference to that type of indicators by which the number of hours that the watch will run, under normal conditions, may be readily ascertained.

As its principal object, this invention contemplates the provision of a winding indicator which may be readily applied to any watch or clock of standard make, and by inspection of which the observer may readily determine whether or not the main spring is fully or partially wound or run down.

A still further object of this invention resides in the provision of an indicator in which the indicating arm is automatically returned to its initial position upon the rewinding of the main spring.

The above and additional objects are accomplished by such means as are illustrated in the accompanying drawings, described in the following specification and then more particularly pointed out in the claim which is appended hereto and forms a part of this application.

With reference to the drawings, wherein I have illustrated the preferred embodiment of my invention as it is reduced to practice, and throughout the several views of which similar reference numerals designate corresponding parts: Figure 1 is a front elevation of a clock dial equipped with a modified form of the indicator; Fig. 2 is a section on the line 5—5 of Fig. 1; and Fig. 3 is a section on the line 6—6 of Fig. 1.

Referring to the drawing the numeral 20 indicates a pinion wheel keyed to the main shaft 21 of a main spring 22. Arranged for sliding contact with the inner face of the clock dial 23 is a rack bar 24, one terminal of which carries a laterally projecting pin

25, operating in a horizontally extending slot 26 formed on the face of the dial. The pin 25 is provided with a headed portion 55 27, which may be formed with an upwardly extending arm 28 adapted to serve as an indicator arm and arranged to move across the graduations 29 formed on the face of the clock dial 23 and immediately above the 60 slot 26. While the ratio of the number of teeth formed on the rack bar 24 to the number of teeth on the periphery of the pinion 20 is an arbitrary matter governed entirely by the conditions concurrent with the application of the device, it may nevertheless be set forth by way of explanation that in practice it is sometimes desirable to construct the rack bar with a hundred teeth and the pinion with ten teeth, this ratio having 70 been found to be the most efficient and practical in moving the indicator arm 28 the required distance across the face of the clock dial.

The operation of the invention is as follows: The rewinding of the main spring acts to draw the rack bar to the right of the clock dial, thus bringing the indicator arm 28 in registration with the up mark on the clock face, and, as the main spring expands, the 80 pinion 20 acts to move the rack bar across the face of the clock dial toward the left, thus advancing the indicator arm 28 over the graduation marks 29, and finally into registration with the down mark. 85

In reduction to practice, I have found that the form of my invention, illustrated in the drawings and referred to in the above description, as the preferred embodiment, is the most efficient and practical; yet, realizing that the conditions concurrent with the adoption of my device will necessarily vary, I desire to emphasize the fact that various minor changes in details of construction, proportion and arrangement of parts may 95 be resorted to, when required, without sacrificing any of the advantages of my invention, as defined in the appended claim.

What I claim is:

A chronometric spring indicator comprising a pinion fixed to the main spring shaft, a horizontally sliding rack bar provided with rack teeth on its lower edge in mesh with the teeth of the pinion, a dial provided

with a horizontal slot and adjacent indicator scale, said rack bar having a pin projecting from one side near the end thereof through said slot, and a pointer arm connected to said pin to move across said slot to indicate the condition of the main spring of the chronometer.

In testimony whereof I affix my signature in presence of two witnesses.

FREDERICK C. HOWARD.
